UNITED STATES PATENT OFFICE.

GEORGE F. DAVISON, OF LA SALLE, ILLINOIS, ASSIGNOR OF ONE-HALF TO DAVID RIORDAN, OF LA SALLE, ILLINOIS.

WATER-CLOSET CONSTRUCTION.

Application filed April 15, 1922. Serial No. 553,045.

To all whom it may concern:

Be it known that I, GEORGE F. DAVISON, a citizen of the United States, residing at La Salle, in the county of La Salle and 5 State of Illinois, have invented new and useful Improvements in Water-Closet Constructions, of which the following is a full, clear, concise, and exact description, reference being had to the accompanying drawing, forming a part of this specification.

My invention relates to water closet construction.

It frequently happens, when the valve which controls the flow from the tank to 15 the bowl has been unseated, that the bowl will overflow before the valve will be again seated, causing an overflow onto the floor of the bathroom, which sometimes causes a great deal of damage to the building.

20 One of the objects of my invention is to provide means whereby, if it appears that the bowl is likely to overflow before the valve seats, the valve can be forced to its seat manually, thus preventing any further flow from the tank to the bowl.

Another object of my invention is to provide means whereby if it appears probable 30 that there is danger of a severe freeze the valve can be adjusted so as to permit a slight flow of water continuously.

In the drawings in which several embodiments of my invention are shown—

Figure 1 is a front elevation of a water 35 closet tank provided with my improvement;

Fig. 2 is a front elevation showing a different form of my device;

Fig. 3 is a front elevation showing still another form of my device;

Fig. 4 is a view showing a detail of an 40 attaching means;

Fig. 5 is a view showing a detail of construction;

Fig. 6 is a section on the line 6—6 of Fig. 45 5; and

Fig. 7 is a detail view showing another feature of construction.

Referring first to the construction shown in Fig. 1, this is of the type having a pressure-seated buoyant flush valve 10 which 50 may be freed from its seat by means of a manually operable lever 11 to permit the buoyant valve 10 to rise because of its buoyancy, the valve 10 remaining open until the water in the tank 12 is lowered sufficiently

to permit the valve 10 to be seated again 55 on its valve seat 13. Thereafter, water flows into the tank 12 through the usual float valve until the tank 12 is filled to the level maintained by the float valve. As the float valve construction referred to is well-known, and forms no part of the combination claimed, it has not been shown in the drawing.

As stated above, it frequently happens, when the valve 10 has been unseated by 60 means of the handle 11, that the bowl will overflow before the valve will be again seated. In order to enable this overflow to be prevented, I provide an emergency attachment by means of which the float 65 valve 10 can be forced downwardly, against the buoyant action of the valve, onto the valve seat 13, to prevent any further flow of water from the tank 12 into the bowl. This emergency attachment, as exemplified 70 in Fig. 1, comprises a lever 14, pivotally mounted inside the tank at 15, and having one arm 16 bearing on the buoyant flush valve 10 and the other arm 17 connected to a pull chain 18, which extends out through 75 an opening 19 in position convenient for operation.

In order to enable the device to be readily applied to constructions already installed, I provide a readily attachable bearing for the 80 lever 14, as shown in Fig. 4. This bearing comprises a turnbuckle construction having two foot portions 20 and 21 respectively, which are forced against the opposite sides 85 of the tank respectively, by means of the turnbuckle 22. The lever 14 may be pivotally mounted on the shank 23, which is secured to the foot 20.

In order to provide a bearing or wear-resisting construction where the chain 18 90 passes through the wall of the tank, I provide a metal eyelet 24, as shown in detail in Figs. 5 and 6, which is clamped onto the wall of the tank 12 by means of a nut 25, threaded onto the tubular shank of the 95 eyelet.

As shown in Figs. 5 and 6, this eyelet is provided with a key-hole shaped opening 100 25^a, the upper part of which provides a free passage for the chain, and the lower part of which may be used as a holding device to hold the chain in any desired position. If it appears that there is danger of a severe

freeze, the valve 10 may be maintained a slight distance from its seat by means of the chain 26 to permit a slight continuous flow of water to prevent freezing. The 5 valve may be held in this adjusted position by utilizing the key-hole shaped slot 25^a referred to above. This key-hole may also be utilized to hold the valve positively seated in case it should be desired to positively 10 prevent it from being moved from its seat, for cleaning, repairs, etc.

In operation, if it appears that the bowl 15 is likely to overflow before the water level in the tank 12 is low enough to permit the valve 10 to seat automatically in the usual way, the chain 18 is pulled to force the arm 16 of the lever 14 downwardly to forcibly seat the valve 10 against its buoyant action. Thus, the flow from the tank 12 is cut off 20 and overflow of the bowl is prevented. It is, of course, understood that after the valve has once been pressed to its seat, it will be held there by the pressure of the water in the tank against the buoyant action of the 25 valve.

In Fig. 2 is shown a different form of device for forcing the buoyant valve 10 to its seat. In this construction, the valve 10, the valve seat 13, and the tank 12 may be 30 the same as in the construction previously described. In this form the buoyant valve may be drawn to its seat against its buoyant action by means of a chain 26 passing over a pulley 27, having one end secured to the 35 valve stem 28 of the valve 10, the other end of the pull chain passing out through the eyelet 24 as in the form previously described. The pulley may be secured to the shank 23 of the turnbuckle construction shown and 40 previously described in connection with Fig. 4.

The operation of the construction shown in Fig. 2 is substantially the same as that shown in Fig. 1, that is, in an emergency 45 the valve may be pulled to its seat by pulling on the chain 26.

In Fig. 3 is shown another form of my invention in which the valve 10 may be pushed to its seat 13 in an emergency by 50 means of a jointed push-rod 29, the lower end 30 of which bears on the buoyant valve 10, and the upper end of which extends through an opening in the cover 31 of the tank. Normally the upper joint 32 of the 55 jointed push-rod may be folded down so as to lie flat against the cover 31 of the tank, but in an emergency the joint 32 may be straightened up and the push-rod pressed down to bring it to the full line position

shown in Fig. 3, to press the valve 10 to its 60 seat.

Figure 7 shows a detail of the jointed connection between the upper joint 32 of the push-rod and the lower joint 33. As shown in Fig. 7 these joints are pivotally connected together at 34, the joints being so constructed that when the bevelled lower end 35 of the upper joint 32 comes against the bevelled portion 36 of the lower joint 33, the two joints will be held in alignment with each other. The operation of this device is substantially the same as in the form previously described, that is to say, when it appears that the buoyant valve 10 will not seat automatically in time to prevent overflow of the bowl the upper joint 32 of the push-rod is straightened out and the rod is pushed down into the full line position shown in Fig. 3, pushing the buoyant valve 10 to its 70 seat against its buoyant action.

It will be seen that there is a common idea in all of the valves, that of preventing overflow of the bowl in an emergency by forcing the buoyant flush valve to its seat against the 75 buoyant action of the valve, to cut off the flow of water from the tank to the bowl sooner than it would be cut off automatically in the ordinary operation of the valve.

Having thus described my invention, what I claim as new and desire to secure by Letters Patent of the United States is—

1. The combination with a water closet tank, a buoyant pressure-operated flush valve, and a valve seat therefor, and manually operable means for freeing said buoyant valve from its seat to permit it to rise because of its buoyancy, of means for maintaining said buoyant flush valve submerged but a slight distance from its seat to permit a slight flow of water to prevent freezing.

2. The combination with a water closet tank, a buoyant pressure-seated flush valve, and a seat for said valve, of mechanical means for positively holding said valve submerged, but a slight distance from its seat, comprising a flexible pull member extending from the lower part of the tank to the upper part of the tank and connected to said valve, said tank having an opening through which said pull member extends, and means in said opening for securing said flexible member to hold it in position.

In witness whereof, I have hereunto subscribed my name.

GEORGE F. DAVISON.
